RETAINING BAND FOR ARMATURES

Gerhard P. Lessmann, Pittsburgh, Pa., assignor
to Westinghouse Electric Corporation, East
Pittsburgh, Pa., a corporation of Pennsylvania

Application September 20, 1949, Serial No. 116,753

7 Claims. (Cl. 24—27)

1

My invention relates to retaining-bands, and it has more particular relation to the banding of high-speed armatures of direct-current machines, or other dynamo-electric machines.

There are known types of banding, of which the Lynn Patent 2,397,187 is an example, in which the ends of the banding-wire are bent back, in hairpin fashion, alongside of the main body of the banding, and in which the bent-back ends are held to the main body of the banding by means of banding-clips which are laid under the band, and then bent back on top of the band, and soldered together with the banding-wire. It has been found that these banding-clips will open up under the influence of centrifugal force, if the soldered joints are defective in any way. As soon as these banding-clips are bent up in a radial direction, the bent-back end of the interlock-wire is also free to move out radially, so that it will eventually open up the hairpin-turn and permit the banding-wire to unravel.

The object of my present invention is to provide a new type of banding-clip means, which will have sufficient strength to prevent its opening up, under the influence of centrifugal force, even though the solder should be melted out or omitted altogether.

An exemplary form of embodiment of my invention is shown in the accompanying drawing, wherein:

Figure 1 is a fragmentary longitudinal sectional view of a portion of a direct-current dynamo-electric machine, with a conventional or schematic showing of a band, applied on one end of the armature,

Fig. 2 is a developed view of the band, on a somewhat larger scale, showing its manner of construction in accordance with my invention,

Fig. 3 is a cross-sectional view on the line III—III in Fig. 2, and

Fig. 4 is an enlarged detail-view showing the manner in which the banding-clip joint is made.

As shown in Fig. 1, my invention is illustrated in application to the armature or rotor-member 3 of a direct-current dynamo-electric machine which has also a field-member or stator-member 4. The invention relates to a banding-wire 5, which is applied, in one or more layers, about the periphery of the coil-ends or end-turns 6 of the armature-winding, to retain the winding against centrifugal force. In accordance with a customary convention, the banding-wire 5 is schematically or diagrammatically shown, not to scale, in Fig. 1, being illustrated as a single layer, in order to avoid confusion of the small-scale

2

drawing, although it is to be understood that the band may consist of two or three layers, or even more. In the particular case illustrated, the band 5 is used to hold the end-turns 6 against a coil-support 7, with an insulating spacer 8 inserted between the upper and lower conductors, and with an insulating layer 9 disposed under the band 5.

The manner of applying the band 5 is illustrated in Fig. 2. The band, as illustrated, comprises the banding-wire 5, a plurality of long underlying lower banding-clips 12, and one or more short upper banding-clips 13. As previously explained, the banding-wire 5 is applied in one or more layers, the particular example illustrated being a three-layer band, as shown in Fig. 3. Each of the layers of the banding-wire 5 has a plurality of turns lying side-by-side around the end-turns 6 or other cylindrical object to be bound. At least one end of the banding-wire has a turned-back end 14, which makes a hairpin loop through another loop 15 of the banding-wire, and which lies against the main body of the banding, as shown in Fig. 2.

The lower banding-clips 12 have intermediate portions 16 which underlie the banding, and end-portions 17 which are bent up over the top of the banding.

One or more of the upper banding-clips 13 is used at the place or places where the turned-back end or ends 14 of the banding-wire are to be held or retained alongside of the main body of the banding. These upper banding-clips 13 have an intermediate portion 18 which overlies one or more end-turns of the top layer of the banding-wire 5, as shown in Figs. 2 and 3. The inner ends 19 of these upper banding-clips 13 underlie one or more intermediate turns of said top layer of the banding-wire 5. This construction is obtained by laying down said inner ends 19 of the upper banding-clips 13 before said intermediate turns are wound. Then, when the necessary number of intermediate turns have been wound on top of the inner ends 19 of the upper banding-clips 13, the winding-operation is interrupted long enough to bend the remainder of the upper banding-clips 13 up out of the way, after which the winding is completed, and the intermediate portions 18 are then laid down over the end-turn or turns of the top layer of the banding-wire.

As shown more particularly in Fig. 4, the outer end 21 of each of the upper banding-clips 13 is then bent down vertically, to overlie, or lie snugly against, the side edge of the banding, and the outer end 21 is then bent horizontally, at 21', to

overlie the end 22 of a lower banding-clip 12, before the latter is bent up around the banding. The outer end 21 of the upper banding-clip 13 is long enough to extend only about half as far beyond the main body of the banding, as said end 22 of the corresponding lower banding-clip 12. The extending end-portion 22' of this end of the lower banding-clip 12 is then bent up and over, so as to overlie the horizontal portion of the outer end 21 of the upper banding-clip 13, thus providing a triple-layer clip-end, as shown at 23 in Fig. 4.

Finally, the triple-layer clip-end 23 is bent up or back against the intermediate vertical portion of the outer end 21 of the upper banding-clip 13, as shown in dotted lines in Fig. 4. In making this bend or fold of the triple-layer clip-end 23, care must be taken to see to it, when bending, that the clip remains tight. To this end, it is quite desirable that the extreme tip 24 of the folded-back end-extension 22', which overlay the horizontal portion of the outer end 21 of the upper banding-clip, before this bending or folding-operation of the triple-layer clip-end was made, should extend back almost to the bend 21' between the vertical and horizontal portions of said outer end 21 of the upper banding-clip 13. Thus, when the upward folding or bending of the triple-layer clip-end 23 is made, the end-tip or edge 24 will press the bend 21' tightly in, against the main body of the banding, thus keeping the clip tight.

As has been customary, when using other forms of banding-clips, one of these improved banding-clip assemblies is placed near, but not quite at, the extreme end 26 of the backwardly bent hairpin-extension 14, and this extreme end 26 is again folded back on the outside of the banding-clip assembly, after the clip has been secured in place, as shown in Fig. 2. In the present instance, such an operation brings the doubled-back end 26 of the banding-wire 11 against the outside of the folded-back triple-layer clip-end 23, so as to help to hold said clip-end in place.

In accordance with the previous practice, I preferably solder all of the retaining-band parts together, particularly the clips and the wires, after the winding of the banding-wire has been completed and the clips have been bent into their final positions. As a result of my banding-clip construction, however, there is only a small leverage which the centrifugal force of a banding-clip can have, upon the loops or bends 21' in my upper banding-clips 13, in the completed or vertically up-bent position of my triple-layer clip-ends 23; and this leverage is small enough so that it will not deform the finished banding-clip assembly, even without any soldering.

While I have illustrated and described my invention in a single preferred form of embodiment, I wish it to be understood that various changes may be made, without departing from the essential spirit of my invention, in various details of folding, numbers of turns, numbers of layers, integral and separate parts, and the like. I desire, therefore, that the appended claims shall be accorded the broadest construction consistent with their language.

I claim as my invention:

1. A retaining-band comprising a banding-wire having one or more layers, each layer having a plurality of turns lying side-by-side around an object to be bound, in combination with a plurality of banding-clip means having interme-

diate portions which underlie the banding and having other portions which overlie the tops and side edges of the banding, at least one of said banding-clip means including a clip-joint at one side edge of the banding, said clip-joint comprising an upper clip-end which overlies the top of the banding and said side edge of the banding and also overlies a corresponding end-extension of the underlying banding-portion, said upper clip-end being long enough to extend about half as far beyond said side edge of the banding as said end-extension of the underlying band-portion, the portion of said end-extension which extends beyond said upper clip-end being bent to overlie said upper clip-end to provide a triple-layer clip-end, and said triple-layer clip-end being bent back against an intermediate portion of said upper clip-end, keeping said banding-clip means tight.

2. The invention as defined in claim 1, characterized by said one of said banding-clip means having a portion which underlies one or more intermediate turns of the top layer of the banding-wire.

3. A retaining-band comprising a banding-wire having one or more layers, each layer having a plurality of turns lying side-by-side around an object to be bound, at least one end of said wire having a turned-back end lying against the main body of the banding, in combination with a plurality of banding-clip means having intermediate portions which underlie the banding and having other portions which overlie the tops and side edges of the banding, at least one of said banding-clip means including a clip-joint at one side edge of the banding at a point suitable for retaining said turned-back end of the banding-wire, said clip-joint comprising an upper clip-end which overlies the top of the banding and said side edge of the banding and also overlies a corresponding end-extension of the underlying banding-portion, said upper clip-end being long enough to extend about half as far beyond said side edge of the banding as said end-extension of the underlying band-portion, the portion of said end-extension which extends beyond said upper clip-end being bent to overlie said upper clip-end to provide a triple-layer clip-end, and said triple-layer clip-end being bent back against an intermediate portion of said upper clip-end, keeping said banding-clip means tight.

4. The invention as defined in claim 3, characterized by at least one of said triple-layer bent-back clip-ends being spaced back from the extreme end of said turned-back end of the banding-wire, and said extreme end being again turned back over said triple-layer bent-back clip-end.

5. A retaining-band comprising a banding-wire, a plurality of long underlying lower banding-clips, and one or more short upper banding-clips, the banding-wire having one or more layers, each having a plurality of turns lying side-by-side around an object to be bound, said lower banding-clips having intermediate portions which underlie the banding, at least one of said upper banding-clips having an intermediate portion overlying one or more end-turns of the top layer of the banding-wire, the inner end of said upper banding-clip underlying one or more intermediate turns of said top layer of the banding-wire, the outer end of said upper banding-clip overlying the end of a corresponding lower banding-clip and being long enough to extend about half as far beyond the main body of the banding as said

end of said corresponding lower banding-clip, the extending end of said end of said lower banding-clip being bent over to overlie said outer end of the upper banding-clip to provide a triple-layer clip-end, and said triple-layer clip-end being bent back against an intermediate portion of said upper banding-clip, keeping said clip tight.

6. A retaining-band comprising a banding-wire, a plurality of long underlying lower banding-clips, and one or more short upper banding-clips, the banding-wire having one or more layers, each having a plurality of turns lying side-by-side around an object to be bound, at least one end of said wire having a turned-back end lying against the main body of the banding, said lower banding-clips having intermediate portions which underlie the banding, at least one of said upper banding-clips having an intermediate portion overlying one or more end-turns of the top layer of the banding-wire at a point suitable for retaining said turned-back end of the banding-wire, the inner end of said upper banding-clip underlying one or more intermediate turns of said top layer of the banding-wire, the outer end of said upper banding-clip overlying the end of a corresponding lower banding-clip and being long enough to extend about half as far beyond the main body of the banding as said end of said

corresponding lower banding-clip, the extending end of said end of said lower banding-clip being bent over to overlie said outer end of the upper banding-clip to provide a triple-layer clip-end, and said triple-layer clip-end being bent back against an intermediate portion of said upper banding-clip, keeping said clip tight.

7. The invention as defined in claim 6, characterized by at least one of said triple-layer bent-back clip-ends being spaced back from the extreme end of said turned-back end of the banding-wire, and said extreme end being again turned back over said triple-layer bent-back clip-end.
